UNITED STATES PATENT OFFICE.

LYMAN C. REED, OF NEW ORLEANS, LOUISIANA.

SYSTEM OF ELECTRIC METERING.

SPECIFICATION forming part of Letters Patent No. 645,129, dated March 13, 1900.

Application filed November 3, 1898. Serial No. 735,722. (No model.)

To all whom it may concern:

Be it known that I, LYMAN C. REED, a citizen of the United States, residing at New Orleans, in the parish of Orleans and State of Louisiana, have invented new and useful Improvements in Systems of Electric Metering, of which the following is a specification.

In an application for patent filed by me concurrently herewith, Serial No. 735,606, I have disclosed certain improvements in the art of electric metering, consisting in the employment of a plurality of meters of different capacities and means for switching said meters into the circuit separately, the object of the invention being to secure accurate registration of the current consumed by an installation through all ranges of load. The switch employed is actuated by magnets located on opposite sides of an armature secured to the switch-lever, and said magnets are in shunt-circuits which are controlled by the quantity of current flowing through the agency of a thermostatic circuit-controller. My present invention has the same object in view—that is, of securing accurate registration through all ranges of load—and, as in the former case, I employ a plurality of meters of different capacities and a switch for separately cutting said meters into the circuit. Instead of the thermostatic circuit-controller, however, disclosed in the former case I employ a magnetic circuit-controller.

The invention therefore consists of a plurality of meters, a service-circuit through said meters, a switch for separately cutting said meters into said circuit, actuating means for said switch, and a magnetic circuit-controller for said actuating means.

It also consists in certain details of construction of the circuit-controller and combinations of parts, which will be hereinafter more fully described and claimed.

In the drawings forming part of this specification, Figure 1 is a front elevation of the switch, its operating mechanism, and the magnetic circuit-controller therefor. Fig. 2 is a side elevation of the same, and Fig. 3 is a diagrammatic view illustrative of the circuit connections.

Like reference numerals and letters indicate like parts in the different views.

In a metallic box or casing 1 are mounted

on an insulating-block 2 four sets of switch-contacts 3 4, 5 6, 7 8, 9 10, the contacts 3 and 7 being connected together by the conductor 11 55 and the contacts 5 and 9 being connected together by the conductor 12. With the switch-contacts are adapted to coöperate the switch-blades 13 and 14 on the switch-lever 15, the said blades being adapted to close the circuits between the members of the pairs of said contacts. The contact 4 is connected through the wire 16 with the positive field-coil 17 of the small meter A, from which leads the wire 18 to the translating devices. The 65 contact 6 is connected through the wire 19 with the negative field-coil 20 of the small meter A, from which leads the wire 21 to the translating devices. The contact 8 is connected through the wire 22 with the positive field-coil 23 of the large meter B, from which leads the wire 24 to the translating devices, and the contact 10 is connected through the wire 25 with the negative field-coil 26 of the large meter B, from which leads the wire 27 75 to the translating devices. Each of the meters illustrated is of the ordinary Thomson three-wire type; but it is obvious that a two-wire meter of the same kind may be employed in its stead or a two or three wire meter of any 80 kind may be used. The neutral wire 28 leads from the translating devices to the main service neutral 29. The switch-contacts referred to are mounted upon insulating-blocks 30 30, secured to the under side of the insulating-block 2, and secured to opposite sides of the box or casing 1 are insulating-blocks 31 32. On the block 31 are binding-poles 33 34, from the former of which leads the wire 19 and from the latter of which the wire 16. On the 90 block 32 are secured binding-poles 35 36, from the former of which leads the wire 25 and from the latter of which the wire 22. These binding-poles are connected with the switch-contacts referred to, as shown in Fig. 3 of the 95 drawings. The switch-lever 15 is fulcrumed at 37 to cross-bars 38, secured to the box or casing 1, and has secured to it an armature 39. Attached to said armature and leading downwardly therefrom is an extension 40 of the lever 15, to which is attached an insulating-block 41. The said block has secured to it and extending in opposite directions therefrom contacts 42 43, the same being adapted

to coöperate with similar fixed contacts 44 and 45, respectively. The lever 15 is adapted to be rocked on its fulcrum 37 for the purpose of switching the current from one meter 5 to the other by means of double-pole magnets 46 47, the same being secured to the metallic box or casing 1, and said box or casing serving as a yoke for the two parts of each of said magnets. The armature 39 plays between 10 the poles of these magnets, and when one is energized the armature will be attracted in one direction to shift the lever 15, and when the other is energized the armature will be attracted in the other direction to shift said lever in a direction opposite that in which it 15 was formerly moved.

The magnets referred to are in shunt-circuits, which are controlled by a magnetic circuit-controller now to be described. Secured 20 to the metallic casing 1, beneath the magnets 46 and 47, is an insulating-block 48, on which are mounted binding-poles 49 50 51. The positive service-wire 52 is connected to the binding-pole 49, the negative service-wire 53 25 is connected to the binding-pole 50, and the neutral service-wire 29 is connected to the binding-pole 51. In front of the insulating-block 48 and the binding-poles carried thereby are the frames of magnets 54 55, which are 30 secured to the box or casing 1 by screws or other analogous means, the said box or casing serving as a yoke to produce a double-pole magnet. An extension 56 of the positive service-wire 52 is wound upon the core of the 35 magnet 54 and is connected through the wire 57 with the switch-contacts 3 and 7. An extension 58 of the negative service-wire is wound upon the core of the magnet 55 and is connected through wire 59 with the switch- 40 contacts 5 and 9. It will thus be seen that the magnets 54 55 are in series with the meters A and B. The contacts 44 and 45, heretofore referred to, are attached to an insulating bar or strip 60, secured to the frames of 45 the magnets 54 55. Also secured to the frames of said magnets is a supporting-bracket 61. Pivoted to the bracket 61 is a soft-iron armature 62, which plays between the poles of the magnets 54 55. When said magnets are 50 energized by the flow of current through the coils thereof, the armature 62 is turned in a direction parallel to the lines of force between the positive and negative poles thereof, the extent of said movement being greater or less, 55 according to the current-flow. Movement of said armature is also retarded and regulated by means of a coil-spring 63, one end of which is attached to said armature and the other adjustably mounted by means of a set-screw 64. 60 Secured to the armature 62 and extending outwardly therefrom is an arm 65, having a contact-point 66 at its outer end which is insulated at 67 from the main portion of said arm. The contact-point 66 is connected 65 through the wire 68 with the binding-pole 51, to which the service neutral 29 is attached. Located on opposite sides of the contact-point

66 are contacts 69 70, the contact 69 being connected through the wire 71 to the contact 45 and the contact 70 being connected through 70 the wire 72 to the contact 44. The wire 73 leads from the positive service-wire 52 to the coils of the magnet 46, and from the latter leads the wire 74 to the contact 43 on the switch-lever 15. The wire 75 leads from the positive service-wire 52 to the coils of the magnet 47, and from the latter leads the wire 76 to the contact 42 on the switch-lever 15.

If the small meter A is intended to measure, say, ten per cent. of the load capacity of the large meter B, the spring 63 will be so adjusted by means of the set-screw 64 that on all loads of ten per cent. of the large meter's capacity or less the armature 62 will be held in such position that the contact-point 66 is 80 out of engagement with the contact 69. If, however, the load increases beyond that which it is intended that the small meter shall measure, contact will be made between the point 66 and the contact 69. Conversely, during the action of the large meter B the current flowing through the coils of the magnets 54 55 will energize the same sufficiently to hold contact-point 66 away from the contact 70. When the load decreases, however, to 90 the point at which it is intended that the small meter shall be thrown into operation, the strength of the magnets 54 55 likewise decreases and through the spring 63 the contact-point 66 will be drawn down into engagement 95 with the contact 70.

When the small meter is in operation, the circuit will be as illustrated in Fig. 3 of the drawings, the positive flow being over the following path: positive service-wire 52, coil 105 56, wire 57, switch-contact 3, blade 14 on switch-lever 15, switch-contact 4, wire 16, positive field 17 of meter A, and wire 18 to translating devices, returning over neutral wire 28 to service neutral 29; and the negative flow over the following path: negative service-wire 53, coil 58, wire 59, switch-contact 5, blade 13 on switch-lever 15, switch-contact 6, wire 19, negative field 20 of meter A, and wire 21 to translating devices, returning over neutral wire 28 to service neutral 29. When the load increases beyond that which the small meter is intended to measure, the armature 62 will be turned against the action of the spring 63, and contact will be made between 110 the point 66 and the contact 69. The shunt-circuit through the magnet 46 will now be closed, the flow of current being as follows: positive service-wire 52, wire 73, coils of magnet 46, wire 74, contacts 43 45, wire 125 71, contact 69, contact-point 66, and wire 68 to service neutral 29. As the magnet 46 is now energized it will attract the armature 39, carried by the switch-lever 15, and shift the blades 13 14 so as to close the circuit between 130 the contacts 10 and 9 and 8 and 7, respectively. During this movement of the lever 15, however, the contact 43 passes out of engagement with the contact 45, and the shunt-

circuit referred to is broken at this point. It will therefore be seen that said shunt-circuit is closed for but an instant of time—only long enough for the magnet 46 to act to shift the switch-lever. It will also be observed that the shunt-circuit is broken at a different point from that at which it is closed. With the switch-lever in the position last described the meter B will be in circuit and the meter A out of circuit, and the flow of current will be as follows: from positive service-wire 52 through coil 56, wire 57, switch-contact 7, blade 14 on switch-lever 15, switch-contact 8, wire 22, positive field 23 of meter B, and wire 15 to translating devices, returning over neutral wire 28 to service neutral 29, and from negative service-wire 53 through coil 58, wire 59, switch-contact 9, blade 13 on switch-lever 15, switch-contact 10, wire 25, negative field-coil 26 of meter B, and wire 27 to translating devices, returning over neutral wire 28 to service neutral 29. It will be observed that after the shunt-circuit through the magnet 46 has been broken between the contacts 43 and 45 during the movement of the lever 15 to switch in large meter B engagement is had between the contacts 42 and 44. If now the load decreases below that which the large meter B can measure accurately and to that at which it is intended the small meter A shall act, the flow of current through the coils 56 58 will also decrease and the strength of the magnets acting upon the armature 62 will diminish. The armature 62 will therefore through the action of the spring 63 be thrown into such position as to bring the contact-point 66 into engagement with the contact 70. The shunt-circuit through the magnet 47 is thereby closed over the following path: positive service-wire 52, wire 75, coils of magnet 47, wire 76, contacts 42 and 44, wire 72, contact 70, contact-point 66, and wire 68 to service neutral 29. Magnet 47 being now energized will attract the armature 39 and shift the lever 15 to the position in which it is shown in Fig. 3 of the drawings. The large meter B will thereby be cut out of circuit and the small meter A cut into circuit over the paths heretofore traced. In the movement of the armature 39 toward magnet 47, however, contact will be broken between the contacts 42 and 44, and the shunt-circuit through the magnet 47 will be closed but for an instant of time and will be broken at a different point from that at which it is made.

As was stated in the former application referred to, only a fixed quantity of current is ever switched over, as the circuit is always broken at a definite point, whether the load be on the increase or decrease, so that all loads above a certain percentage of the total capacity of the installation will be measured by the large meter B alone, and all loads below the same point will be measured by the small meter A alone.

The invention has been shown and described in connection with a three-wire sys-

tem of distribution. It is obvious, however, that it is equally well adapted to a two-wire system and may be used on either direct or alternating current.

Having now described my invention, what I claim as new, and desire to secure by Letters Patent, is—

1. In a system of electric metering, the combination of a plurality of meters, a service-circuit through said meters, and an electromagnetic circuit-controller for separately cutting said meters into said circuit. 75

2. In a system of electric metering, the combination of a plurality of meters, a service-circuit through said meters, a switch for separately cutting said meters into said circuit, electromagnets for actuating said switch, shunt-circuits through said magnets, and an electromagnetic circuit-controller for said shunt-circuits. 80

3. In a system of electrical metering, the combination of a plurality of meters, a service-circuit through said meters, a switch for separately cutting said meters into said circuit, electromagnets for actuating said switch, shunt-circuits through said magnets, and an automatic, electromagnetic circuit-controller for said shunt-circuits actuated by the quantity of current flowing. 95

4. In a system of electric metering, the combination of a plurality of meters, a service-circuit through said meters, a switch for separately cutting said meters into said circuit, actuating means for said switch, and an electromagnetic circuit-controller for said actuating means. 100

5. In a system of electric metering, the combination of a plurality of meters, a service-circuit through said meters, a switch for cutting said meters into said circuit, electromagnets for actuating said switch, shunt-circuits through said magnets, and an electromagnetic circuit-controller in said service-circuit for closing said shunt-circuits. 105

6. In a system of electric metering, the combination of a plurality of meters, and an electromagnetic circuit-controller in series with said meters for separately cutting said meters into the circuit. 115

7. In a system of electric metering, the combination of a plurality of meters, a switch for cutting said meters into said circuit, electromagnets for actuating said switch, shunt-circuits through said magnets, and an electromagnetic circuit-controller in series with said meters for separately closing said shunt-circuits. 120

8. In a system of electric metering, the combination of a plurality of meters, a service-circuit through said meters, a switch for cutting said meters into said circuit, electromagnets for actuating said switch, shunt-circuits through said magnets, and a circuit-controller for said shunt-circuits, comprising an electromagnet in the service-circuit, a contact-point operated thereby, and contacts in said shunt-circuits, through which and said con- 125
130

tact-point, said shunt-circuits are adapted to be separately closed.

9. In a system of electric metering, the combination of a plurality of meters, a service-circuit through said meters, a switch for cutting said meters into said circuit, electromagnets for actuating said switch, shunt-circuits through said magnets, and a circuit-controller for said shunt-circuits, comprising an electromagnet in the service-circuit, an armature therefor, a contact-point operated by said armature, and contacts in said shunt-circuits, through which and said contact-point said shunt-circuits are adapted to be separately closed.

10. In a system of electric metering, the combination of a plurality of meters, a service-circuit through said meters, a switch for cutting said meters into said circuit, electromagnets for actuating said switch, shunt-circuits through said magnets, and a circuit-controller for said shunt-circuits, comprising an electromagnet in the service-circuit, a rotary armature therefor, an arm connected with and operated by said armature, a contact-point carried by but insulated from said arm, and contacts in said shunt-circuits, through which and said contact-point said shunt-circuits are adapted to be separately closed.

11. In a system of electric metering, the combination of a plurality of meters, a service-circuit through said meters, a switch for cutting said meters into said circuit, electromagnets for actuating said switch, shunt-circuits through said magnets, and a circuit-controller for said shunt-circuits, comprising an electromagnet in the service-circuit, a rotary armature therefor, an adjustable spring for controlling the movements of said armature, a contact-point operated by said armature, and contacts in said shunt-circuits, through which and said contact-point said shunt-circuits are adapted to be separately closed.

12. In a system of electric metering, the combination of a plurality of meters, a service-circuit through said meters, a switch for cutting said meters into said circuit, electromagnets for actuating said switch, shunt-circuits through said magnets, and a circuit-controller for said shunt-circuits, comprising a double-pole electromagnet, the cores of which are surrounded by helices connected, respectively, with the positive and negative service-wires, an armature for said magnet, a contact-point

operated by said armature and connected with the service neutral, and contacts in said shunt-circuits through which and said contact-point said shunt-circuits are adapted to be separately closed.

13. In a system of electric metering, the combination of a plurality of meters, a service-circuit through said meters, a switch for cutting said meters into said circuit, electromagnets for actuating said switch, shunt-circuits through said magnets, and a circuit-controller for said shunt-circuits, comprising a double-pole electromagnet, the cores of which are surrounded by helices connected, respectively, with the positive and negative service-wires, a rotary armature movable between the poles of said magnet, a spring for controlling the movements of said armature, an arm carried by said armature, a contact-point secured to but insulated from said arm and connected to the service neutral, and contacts in said shunt-circuits through which and said contact-point said shunt-circuits are adapted to be separately closed.

14. In a system of electric metering, the combination of a plurality of meters, a service-circuit through said meters, a switch for cutting said meters into said circuit, including a switch-lever, an armature carried by said lever, contacts 42, 43, also carried by said lever, electromagnets on opposite sides of said armature for actuating said lever, contacts 44, 45, which the contacts 42, 43, are adapted to respectively engage, contacts 69, 70, connected with the contacts 45 and 44, respectively, a shunt-circuit through one of said magnets including the contacts 43, 45, and 69, a shunt-circuit through the other of said magnets including the contacts 42, 44, and 70, and a circuit-controller for said shunt-circuits, comprising an electromagnet in said service-circuit, and a contact-point operated thereby adapted to engage the contacts 69 and 70 for separately closing said shunt-circuits, the shunt-circuit which is closed thereby being almost immediately broken between the contacts 42 and 44 or 43 and 45.

In testimony whereof I have hereunto set my hand in presence of two subscribing witnesses.

LYMAN C. REED.
